Primary Examiner — Catherine A Tuttle*(74) Attorney, Agent, or Firm* — Schwegman Lundberg & Woessner, P.A.CLAIM

The ornamental design for a cosmetic package, as shown and described.

DESCRIPTION

FIG. 1 is a front view of the cosmetic package embodying our new design, the side shown being hemicylindrical in form;

FIG. 2 is a top view thereof; and,

FIG. 3 is a bottom view thereof.

The broken lines are included for the purpose of illustrating the portions of the cosmetic package that form no part of the claimed design. The vertical dashed lines symbolic of color and opposite side of FIG. 1 likewise form no part of the claimed design.
